BURT D. STEVENS, OF RIVERSIDE, ILLINOIS, ASSIGNOR TO THE MIEHLE PRINTING PRESS & MANUFACTURING COMPANY, OF CHICAGO, ILLINOIS, A CORPORATION OF ILLINOIS.

DELIVERY MECHANISM FOR PRINTING-PRESSES.

1,156,940.

Specification of Letters Patent. Patented Oct. 19, 1915.

Application filed November 10, 1913, Serial No. 800,016. Renewed March 17, 1915. Serial No. 15,081.

To all whom it may concern:

Be it known that I, BURT D. STEVENS, a citizen of the United States, residing at Riverside, in the county of Cook and State 5 of Illinois, have invented certain new and useful Improvements in Delivery Mechanism for Printing-Presses, of which the following is a specification.

The invention has for its object the provision of mechanism to effect a delivery of printed sheets from the impression cylinder to the pile of finished sheets in such a way as to insure the uniform stacking of the same in a vertical pile and to obviate the 15 danger of offset or blur due to the relative movement or shifting of one sheet upon another.

Ordinarily as each sheet is carried by the delivery mechanism to and deposited upon 20 the pile of sheets previously printed there is a tendency of the sheet to sag at the last moment before it is released by the gripper of the delivery mechanism and to wipe over the freshly printed surface of the preceding 25 sheet on the pile, and it is for the purpose of avoiding this action of the delivery and causing the newly delivered sheet to drop vertically into place on the top of the pile that the present invention is designed.

30 In order that the invention and the manner of its operation may be readily understood a preferred embodiment of the same is set forth in the accompanying drawing and in the following description based 35 thereon.

The invention is, however, obviously susceptible of embodiment in other and varied 40 constructional forms wherefore the drawing and description are to be construed in an illustrative and not in an unnecessarily limiting sense.

In the drawing is set forth in a diagrammatic manner the impression cylinder 11, the feed board 12, the bed plate 13, the delivery 45 tape 14, and the delivery table 15, upon which latter the printed sheets are deposited. In the form of delivery mechanism shown the tape 14 travels about the companion rollers 16 and 17 which are driven in unison 50 by the sprocket chain 18 at a peripheral speed corresponding to that of the cylinder 11. The sheet 19 having received its impression from the form upon the bed 12 while upon the impression cylinder 11, is

released by the grippers 20 and engaged by 55 the grippers 21 which latter draw the sheet over the supporting slats 22 toward the delivery table 15, whereby the sheet is continuously under gripper control until delivered. It is to be understood that while 60 pinching grippers are represented at 20 and 21, any suitable form of gripper mechanism may be employed which takes hold of the sheet as distinguished from a carrier upon which the sheet merely rests without being 65 engaged thereby.

As it is impracticable to extend the supporting slats 22 over the table 15 so as to support the paper until it is finally released by the grippers 21, the rear portion of the 70 sheet 19 ordinarily drops upon the pile of sheets indicated at 21^a as soon as it leaves the supporting slats and consequently wipes over the surface of the sheets 21^a during the final portion of its movement and until it is 75 released by the grippers 21 and permitted to fall upon the other sheets.

In order to hold the freshly printed sheet in substantially the plane of the delivery and out of contact with the pile of printed 80 sheets until it is finally released and permitted to drop thereon I have provided a suction restraining device which operates upon the trailing free portion of the sheet so as to maintain the same taut. As illustrated this restraining device consists of a suction pipe 23 extending horizontally beneath the path of the sheet and having upon its upper face a series of orifices 24 through which suction generated by the exhaust fan 90 25 is caused to act upon the sheet after it leaves the supporting slats, whereby the same is maintained under tension as it is drawn forward by the grippers 21. The suction pipe 23 is arranged adjacent that 95 edge of the table 15 which is nearest the impression cylinder and means are provided to interrupt the suction action at the instant following the release of the sheet by the grippers 21. The interruption of the suction 100 takes place substantially simultaneously with the release of the sheet by the grippers but just sufficiently subsequent thereto to overcome the momentum of the sheet and to permit it to drop vertically on to the pile 105 after its release.

While the means provided for interrupting the suction form of themselves no part

of the present invention and various forms of mechanism may be employed for this purpose, I have indicated, by way of illustration, interrupting means comprising a slide 5 arranged to cover and uncover the apertures 24 when acted upon by a tappet 27 carried by the delivery tape, the return of the slide being effected, for instance, by a spring not shown.

10 From the foregoing it will be readily understood that the sheet of paper carried by the delivery tape is retarded in its trailing operation and thus prevented from sagging into contact with the pile of printed sheets 15 over which it is passing; that in the instant following its release by the grippers of the delivery mechanism the suction acting upon its rear edge is likewise interrupted and the sheet is permitted to drop vertically upon 20 the pile of previously printed sheets thus avoiding any blurring action due to wiping contact between the sheets and also insuring the stacking of the sheets in a uniform pile.

The suction device is fixed or stationary 25 during its action upon the printed sheet, and therefore it does not impart any positive feeding movement to the printed sheet, but acts in opposition to the feeding movement imparted to the printed sheet by the 30 conveying mechanism, thereby to absolutely prevent any endwise movement of the printed sheet when it settles upon the pile of printed sheets. Moreover, the suction device acts upon the unprinted side of the 35 printed sheet, and thereby smearing of the freshly printed matter is effectually obviated without in any manner whatsoever interfering with or reducing the restraining influence of the suction device.

40 I claim:

1. The combination with a printing couple, of sheet delivery mechanism comprising gripper means arranged to take the sheet from the printing couple and to convey the 45 same therefrom, restraining means acting concurrently with the grippers but upon the unprinted side of the rear portion of the sheet to exert tension thereon in opposition to the grippers and the restraining means arranged to release the sheet in the order named.

2. The combination with a printing couple, of sheet delivery mechanism comprising grippers arranged to engage the front 55 edge of the sheet and to draw the same from the printing couple and to convey the same therefrom, restraining means acting concurrently with the grippers but upon the unprinted side of the trailing portion of the sheet to exert tension thereon in opposition to the grippers, and means to release the sheet from the grippers and to interrupt the action of the restraining means upon the sheet in the order named.

65 3. The combination with a printing couple,

of a delivery mechanism comprising a traveling gripper mechanism for taking and conveying the sheet therefrom, and a suction device arranged to act simultaneously therewith upon the trailing portion of the unprinted side of the sheet to exert a tension thereon, said suction device being stationary during its action on the printed sheet.

4. The combination with a printing couple, of a delivery mechanism, a traveling gripper mechanism for taking and conveying the sheet therefrom, of a suction device arranged to be traversed by the unprinted side of the moving sheet and to exert a tension thereon, said suction device being stationary when acting upon the sheet.

5. The combination with a printing couple, of a delivery mechanism comprising a traveling gripper mechanism for taking and conveying the sheet therefrom, a suction device arranged to act simultaneously therewith upon the trailing portion of the unprinted side of the sheet to exert a tension on the sheet, and means to periodically render the suction device inoperative, said suction device being stationary while acting on the sheet.

6. The combination with a printing couple, of a delivery mechanism comprising a traveling gripper mechanism for taking and conveying the sheet therefrom, a suction device arranged to be traversed by the moving sheet and to exert a tension thereon, and means to interrupt the action of the suction device at substantially the same time that the sheet is released by the conveying mechanism.

7. The combination with a printing cylinder, of a delivery mechanism comprising a traveling gripper mechanism for taking and conveying the sheet therefrom, a suction device arranged to be traversed by the unprinted side of the moving sheet and to exert a tension thereon, and means to periodically render the suction device inoperative, said suction device being stationary while acting on the sheet and disposed at that edge of the delivery table nearest the cylinder.

8. The combination with a printing couple, of a delivery mechanism comprising a traveling gripper mechanism for taking and conveying the sheet therefrom, a suction device arranged to be traversed by the moving sheet and to exert a tension thereon, and means to interrupt the action of the suction device in the instant following the release of the sheet by the conveying mechanism.

9. Sheet delivery mechanism, comprising means for drawing a sheet from an impression member, means acting on the unprinted side only of a sheet for maintaining a tension on the sheet while being drawn by the drawing means, said tension means being stationary when acting on the printed sheet,

means for disconnecting the sheet from the drawing means, and means for subsequently disconnecting the sheet from the tension means.

5 10. Sheet delivery mechanism, comprising means for drawing a sheet from an impression member, a suction device disposed in the path of travel of the sheet for maintaining a tension upon the sheet while said sheet 10 is being drawn by the drawing means, means

for disconnecting the sheet from the drawing means, and means for subsequently interrupting the action of the suction device.

In testimony whereof I have hereunto signed my name in the presence of two subscribing witnesses.
